L. B. WHIPPLE.

LAST.

APPLICATION FILED AUG. 6, 1919.

Patented Feb. 21, 1922.

INVENTOR

Leland B. Whipple
By his Attorney,
Nelson M. Howard

UNITED STATES PATENT OFFICE.

LELAND B. WHIPPLE, OF ROCHESTER, NEW YORK, ASSIGNOR TO FITZ-EMPIRE
DOUBLE PIVOT LAST COMPANY, OF AUBURN, MAINE, A CORPORATION OF
MAINE.

LAST.

1,407,050.

Specification of Letters Patent. Patented Feb. 21, 1922.

Application filed August 6, 1919. Serial No. 315,645.

To all whom it may concern:

Be it known that I, LELAND B. WHIPPLE, a citizen of the United States, residing at Rochester, in the county of Monroe and 5 State of New York, have invented certain Improvements in Lasts, of which the following description, in connection with the accompanying drawings, is a specification, like reference characters on the drawings indicating like parts in the several figures.

This invention relates to lasts and in particular to hinge lasts having a separate forepart and heel part connected by a bonding mechanism arranged to permit relative rotation (or rotation combined with translation) of the last parts to collapse the last and facilitate its removal from a shoe.

Lasts of this type are much subject to criticism because of lack of strength and 20 rigidity, and it is a principal object of the invention to provide a last which will secure all the advantages of lasts of this type without being subject to these disadvantages.

Accordingly, a principal feature of the 25 invention resides in a novel organization of last parts having a dividing cut comprising a re-entrant angle and a simple and inexpensive link-bonding mechanism.

This and other features of the invention, 30 comprising various arrangements and combinations of parts will be understood from the following description which shows a preferred embodiment of the invention, selected for purposes of illustration and shown 35 in the drawing in which,

Fig. 1 is a section view of the last in extended position;

Fig. 2 is a sectional view showing the last in collapsed position.

40 The last has a forepart 10 and a heel part 12, divided by a cut which extends upwardly and forwardly, as at 14, to nearly the center of the last, then extends forwardly as at 16, and then upwardly as at 18 on the forepart. The heel part secant face 20 extends 45 from an intermediate point of the segment 16 and extends upwardly and backwardly to the top of the cone.

The bonding mechanism comprises four rivets 22, 24, 26, 28, the rivets 24, 26 being located approximately in the same horizontal plane, while the rivet 28 is considerably higher than the rivet 22. These rivets are joined by two links 29, 30, as shown, the upper link 29 having a lug 32 arranged to engage a spring 34, seated in a hole 36.

When the last is extended, the side 37 of the re-entrant angle 38 rests upon the surface 16 and affords a firm bearing against torsional stresses, such as are imposed by the leveling machine. At the same time, the last is easily collapsible by pressure and without the use of special tools or jacks. The sloping cut 14 permits the lower secant face on the heel part to pass freely over the corner on the forepart formed by the cuts 14 and 16, without binding, as shown in dotted lines in Fig. 2.

The last described is simple in construction, not easily put out of order, and cheap 70 to manufacture. It is at the same time rigid against the stresses met with in machine shoe-making and is easily collapsible when it is desired to withdraw the shoe.

Having described my invention, what I 75 claim as new and desire to secure by Letters Patent of the United States is:—

A divided last having a cut comprising a re-entrant angle of approximately 90° in the heel part, a corner on the forepart, fitting 80 into said angle when the last is extended, and a contact face extending from said corner downward and substantially rearward to the bottom of the last, and two non-parallel links each pivoted in both last parts 85 arranged one above the other, the lower being substantially horizontal, and the upper being inclined downwardly toward the front, constructed and arranged to swing the heel part upwardly and forwardly past the said 90 corner on the forepart to collapsed position.

In testimony whereof I have signed my name to this specification.

LELAND B. WHIPPLE:
